UNITED STATES PATENT OFFICE.

GEORGE D. NICHOLS, OF NEW CANAAN, CONNECTICUT.

CORSET-CLASP.

SPECIFICATION forming part of Letters Patent No. 430,874, dated June 24, 1890.

Application filed August 29, 1889. Serial No. 322,341. (No model.)

To all whom it may concern:

Be it known that I, GEORGE D. NICHOLS, of New Canaan, in the county of Fairfield and State of Connecticut, have invented a new

5 Improvement in Corset-Clasps; and I do hereby declare the following, when taken in connection with accompanying drawings and the letters of reference marked thereon, to be a full, clear, and exact description of the same, 10 and which said drawings constitute part of this specification, and represent, in—

Figure 1, a face view of the two busks locked together, the one busk A being in the pocket-strip; Fig. 2, a portion of the two busks, 15 showing one eye and stud disengaged; Fig. 3, one eye detached; Fig. 4, a transverse section on line $x-x$ of Fig. 1.

This invention relates to an improvement in that class of clasps for corsets which consist of a pair of busks adapted to be introduced into the edges of the respective parts of the corset, one busk being provided with studs and the other with eyes to engage the studs. In the usual construction the eyes, 20 which are attached to one busk, are constructed with an opening in width corresponding to the body of the stud, the inner end of the opening enlarged, so as to pass over the stud; but such clasps are liable to accidental 25 detachment while on the wearer, and frequently to the great inconvenience of the wearer.

Various devices have been provided to produce a lock for the clasp, so that accidental 30 disengagement is impossible.

My invention relates more especially to a clasp provided with such a locking device; and the invention consists in the peculiar construction of the locking device, as more 35 fully hereinafter described, and particularly recited in the claim.

A represents one busk, to which the usual studs a are applied, and B the second busk, to which the eyes b are applied. The eyes b 40 are made from the usual sheet metal and secured to the busk by rivets or otherwise. The eyes are constructed with their outer end open, so as to form a U-shaped recess d , as seen in Fig. 3, the width of the recess d corresponding substantially to the body of the 45 stud, but less than the head of the stud. The sides of the recess at the outer end diverge,

so as to produce a wide mouth as an entrance to the recess d . The several eyes in the one busk correspond in position to the studs on the other busk, as usual in corset-clasps. Each of the eyes is provided with a latch e , 55 hung upon a pivot f , the said pivot here represented as one of the rivets by which the eyes are secured to the busk, and so that the latches may swing in a plane across the faces 60 of the eyes. The outer ends of the latches are of hook shape, so as to form a shoulder g , which may extend across the recess d , as seen in Fig. 2, leaving an open portion of the recess upon the inside of the shoulder, within 65 which the body of the stud may rest. The latches extend to the rear of the pivot f , to form tails h , and the tails of the latches are each hung to a sliding rod i , which lies flat 70 upon the busk B. This rod i is adapted to slide longitudinally, and so as to turn the latches from the position seen in Fig. 1 to that seen in broken lines in same figure, the position in broken lines taking the shoulders of 75 the latches away from the recesses in the eyes, and so that those recesses will be open for the escape or entrance of the studs. The latches are also provided with a shoulder l , 80 which may strike the other rivet of the eyes, or any suitable stop thereon, which will serve to arrest the swinging movement of the latches when they are in their proper position to close the recesses of the eyes, as seen in Figs. 1 and 2.

The rod i is provided with a suitable spring, 85 here represented as a spiral spring m , and also a torsion-spring n , the tendency of which is to force the rod in the direction to bring the latches to the closed position, as seen in Fig. 90 1, but yield to the movement of the rod to the open position. The outer end of the nose or shoulder g of the latches is beveled outward, so that as the latches are forced against the studs they may automatically give way, so as 95 to pass over the studs.

The two busks are applied to the corset in the usual manner.

To engage the eyes with the studs, they are brought to the position as seen in Fig. 2, and 100 then forced together, so that the nose of the latch will strike the stud on one side, and the opposite side of the recess strike the other side of the stud, and thus forced together the

latch will give way until the eyes have passed onto the studs, and so that the latches may drop upon the rear of the studs, as seen in Fig. 1, and thus interlock the eyes with their 5 respective studs.

The rod is provided with any suitable connection by which the wearer may operate it, as by a stud or knob *r*, adapted to extend through the front of the pocket which in 10 closes the busk *B*, as a convenient handle for operating the rod.

To disengage the clasp, the rod is moved, as indicated in broken lines, Fig. 1, until the several latches have escaped from their 15 respective studs. Then the clasps naturally separate.

It will be understood that either of the springs illustrated will be sufficient to yieldingly hold the latches in the closed position, 20 or that any suitable spring may be employed for that purpose.

I do not wish to be understood as claiming, broadly, a spring-latch as a lock for corset-clasps, as such, I am aware, is not new.

25 I am aware that corset-clasps have been constructed with eyes on one part to engage studs on the other part, and with swinging hooks adapted to interlock with said stud when the parts are closed, and also that such 30 hooks have been connected so that a single movement would operate all the hooks. I

therefore do not wish to be understood as claiming, broadly, such a construction of clasp; but

What I do claim is—

A pair of busks for a corset, the one provided with headed studs *a*, the other with corresponding stationary eye-pieces *b*, the said eye-pieces constructed with a recess at their outer ends, the width of the said recess at its 40 inner end less than the diameter of the head of the stud, the opening into said recess flaring, combined with latches *e*, hung upon a pivot on each of said eye-pieces, one arm of the latch extending forward and constructed 45 at the outer end in hook shape to pass across the said recesses in the eye, the nose of the latch beveled outward across the opening, the other arm of the latches extending rearward beyond their pivots, a vertically-sliding rod 50 hung to the several latches, a spring between the busk and said rod, whereby the latches are yieldingly held in their closed position, the said latches constructed with a shoulder, and the eye-piece with a corresponding stop, 55 against which said shoulder may strike when the latch is in the closed position, substantially as described.

GEORGE D. NICHOLS.
